CLAIM

The ornamental design for a room sensor, as shown and described.

DESCRIPTION

FIG. 1 is a front, bottom, and right side perspective view of a room sensor showing my new design;

FIG. 2 is a front, top, and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings illustrate portions of the room sensor and form no part of the claimed design.

1 Claim, 7 Drawing Sheets
